UNITED STATES PATENT OFFICE.

ISIDORO MARTINEZ, OF LA PEXOR, TEXAS.

DEVICE FOR PICKING COTTON.

Application filed February 23, 1926. Serial No. 90,033.

This invention relates to cotton picking, and the like, the invention having more particular reference to a novel type of a spring harness to be worn by cotton pickers, and the like.

The invention has for an object the provision of an improved spring harness which will enable the wearer to assume an erect position after continual stooping, as required when picking cotton or the like.

A further object is to provide a spring harness of novel construction and arrangement of parts.

For further comprehension of the invention, and of the objects and advantages thereof, reference will be had to the following description and accompanying drawing, and to the appended claims in which the various novel features of the invention are more particularly set forth.

Fig. 1 of the drawing shows my improved spring harness attached to the wearer, as it would appear when in use.

Fig. 2 shows a front elevational view of my improved device.

Fig. 3 shows an enlarged perspective detail view of the spring and means of adjusting same.

Fig. 4 shows a front elevational view of a modification of the spring, used in connection with my improved device.

Fig. 5 shows an enlarged fragmentary detail of the means for angularly adjusting the supporting members.

As here embodied my improved device comprises a breast plate 10, preferably diamond shaped and corrugated, and a supporting frame 11 having extended elements 12 and 13, at right angles thereto. The breast plate 10 is held in position on the wearer, as clearly shown in Fig. 1 of the accompanying drawing, by means of the rear straps 14 and 15 which extend from the breast plate 10 over the shoulder of the wearer and down the back to the foot straps 16 and 17 respectively, the said rear straps 14 and 15 being further supported by the intermediate breast straps 18 and 19 respectively, and by the intermediate rear straps 20 and 21. The supporting frame 11 is held in position on the wearer, as clearly shown in Fig. 1 of the accompanying drawing, by means of the thigh straps 22 and 23, the upper foot straps 24 and 25, and the heretofore mentioned foot straps 16 and 17. It being understood that the above mentioned

and described straps are provided with buckles 26, such as ordinarily used for fastening straps in position, and that suitable shoulder pads 27 and 28, and leg pads 29 and 30, are provided for the comfort of the wearer.

It will be further understood that the rear straps 14 and 15 may be provided with elastic pieces, or may be made entirely of elastic material, so as to permit the wearer to bend over or stoop.

As here embodied my improved device also comprises a coil spring 31, having its lower extremity attached to a lower supporting member 32, and its upper extremity attached to an upper supporting member 33. The lower supporting member 32 and the upper supporting member 33, preferably circular discs, are pivotally attached by means of extended portions 38 to arms 34 and 35, extending from the supporting frame 11 and the breast plate 10. As a means of holding the said lower supporting member 32 and the upper supporting member 33, in any desired angular position, for the purpose as hereinafter set forth, I have provided levers 37 rigidly attached to the extended portions 38 of the lower supporting member and the upper supporting member, and hand screws 39, or any similar suitable screws, threadedly engaged with extensions depending from the arms 34 and 35, as at 40, and having pivotally attached thereto, in a convenient manner a jaw 39' located so as to engage with the free extremity of the said levers 37, as clearly shown in the accompanying drawing. Adjusting the screw 39, results in raising or lowering the jaw 39', thereby moving lever 37, which is rigidly attached to members 38 depending from the supporting members, therefore turning these latter members.

Referring in particular to the modification of my improved device, as shown in Fig. 4 of the accompanying drawing, I have provided two coil springs 41 and 42. It being understood that the two coil springs 41 and 42 are attached to lower supporting members 32 and to upper supporting members 33, similarly attached to the supporting frame 11, and the breast plate 10, respectively, as hereinbefore set forth and described.

Referring in particular to the application and use of my improved device. When the wearer assumes a bent over, or stooped position, the coil spring will support the wearer,

and allow relaxation of the shoulder and back muscles. When the wearer assumes an erect position the coil spring will also support the wearer, and relieve the muscles which have previously been in a bent or strained position.

It will be further understood that the thumb screws will permit the wearer to adjust the angular positions of the upper supporting member and the lower supporting member so as to maintain the coil spring in a fully compressed position, so as to prevent bulging or canting of the said coil spring.

15 Having thus described my invention, what I claim as new and desire to protect by Letters Patent of the United States is as follows:—

1. In a device of the class described, a coil 20 spring, a lower supporting member fastened to the lower end of said coil spring, an upper supporting member fastened to the upper end of said coil spring, a supporting frame pivotally holding said lower supporting member, a breast plate pivotally holding said upper supporting member, and means for holding said upper end and lower supporting members in angular adjusted positions.
2. In a device of the class described, a coil 30 spring, a lower supporting member fastened to the lower end of said coil spring, an upper supporting member fastened to the upper end of said coil spring, a supporting frame pivotally holding said lower supporting member, by means of extended portions depending therefrom, a breast plate pivotally holding said upper supporting member, by means of extended portions depending therefrom, and means for holding said upper and lower supporting members in angular adjusted positions.
3. In a device of the class described, a coil 40

spring, a lower supporting member fastened to the lower end of said coil spring, an upper supporting member fastened to the upper end of said coil spring, a supporting frame pivotally holding said lower supporting member by means of extended portions depending therefrom, a breast plate pivotally holding said upper supporting member, by means of extended portions depending therefrom, and means for holding said upper and lower supporting members in angular adjusted positions, consisting of levers 50 rigidly attached to said extended portions of the said supporting members, arms depending from said supporting frame and breast plate, thumb screws threadedly engaged in said arms, said thumb screws being 55 engaged with the free ends of said levers.

4. A spring harness for cotton pickers and the like, comprising a breast plate, a supporting frame having extended elements at right angles thereto, a supporting member pivotally attached to said breast plate, another supporting member pivotally attached to said supporting frame, a coil spring fastened at one end to one of said supporting members and at the other end to 70 the other of said supporting members, means for holding the said supporting members in angular adjusted positions, and means for holding the said breast plate and supporting frame in position on a wearer, consisting of 75 rear straps extending from the breast plate over the shoulder and down the back of the wearer engaging foot straps, breast straps and intermediate rear straps connected with said rear straps, and the said supporting frame being held in position on the wearer by thigh straps, upper foot straps, and the said foot straps.

In testimony whereof I have affixed my signature.

ISIDORO MARTINEZ
